UNITED STATES PATENT OFFICE

WILLIAM J. DE WITT, OF AUBURN, NEW YORK, ASSIGNOR TO SHOE FORM CO., INC., OF AUBURN, NEW YORK, A CORPORATION OF NEW YORK

SHOE FORM

Application filed March 3, 1930. Serial No. 432,587.

This invention relates to an improvement in a shoe form, more particularly in one of the full form type such as is shown, for example, in my prior Patent No. 1,632,953, dated June 21, 1927. As pointed out in that patent, the heel of the form is made by overlapping portions of the side walls, which portions may be left free and unconnected, as shown in my Patent No. 1,632,954 dated June 21, 1927. One means of joining the portions of the side walls which form the heel is shown in my copending application, Serial No. 376,883, filed June 9, 1929.

The present application is based upon a further development of the full form feature having for its object to provide means whereby the width of the heel may be adjusted as desired, and when so adjusted will remain in such position. A further object of this invention is to provide a full form, the bottom of the heel of such form being open at the rear to permit easy manipulation of the form when it is inserted into a shoe. Other objects will appear from a consideration of the following specification and of the drawings which form a part thereof, and in which:

Fig. 1 is a side elevation of a full shoe form embodying this invention;

Fig. 2 is an end view thereof;

Fig. 3 is a cross section of the heel taken along the lines 3—3 of Fig. 2;

Fig. 4 is a side elevation of a full shoe form illustrating another embodiment of this invention;

Fig. 5 is a rear view of such form; and

Figs. 6 and 7 are end views of other embodiments of this invention, the heel portions being extended in order to illustrate clearly the relation of the portions of the side wall which form the heel.

Referring to the embodiment of my invention illustrated in Figs. 1, 2 and 3, the side walls of the form 10 terminate at the heel in projecting portions or tabs 11 and 12. The tab 11 extends from the upper edge of one side wall, and the tab 12 extends from the middle of the edge of the other side wall, these portions being so related that they substantially interlock, as shown particularly in Fig. 2. The side wall 15, from which the tab

11 projects, is provided with a series of slots 16 laterally spaced, each of which is of a size sufficient to receive the tab 12 projecting from the other side wall 17. It will be noted that the forward movement of the tab 12 in the slot 16 into which it is inserted is limited by a tongue 18 preferably integral with the tab 12. This tongue 18 extends along the outer surface of the wall 15 and its engagement at the root with the forward wall of a slot 16 positively limits the forward movement of the tab 12.

In the embodiment shown in Figs. 4 and 5, the side walls 21 and 22 of the form 20 terminate in projecting tabs 23 and 24 respectively, the tab 24 which projects from the upper edge of the side wall 22 is the same as the tab 11 shown in the first embodiment. The tab 23, however, is preferably made narrower than the tab 12 of this embodiment and is provided at its forward end with a button or rivet 25. In the side wall 22 is provided a longitudinally extending slot 26 into the lower edge of which slots 27 lead. The button 25 enters the main slot 26 and can be therewith introduced into any one of the slots 27, thus positively fixing the size of the heel of the form 20.

In the embodiment shown in Fig. 6, the side wall 31 of the form is provided with a tab 33 having at its outer end a button or rivet 34 which is adapted to enter the desired slot 35 leading from the longitudinally extending main slot 36 formed in the side wall 32. The tab 33 corresponds to the tab 23 of the form 20, but instead of being made integral with its side wall is secured thereto by a rivet or button 37. It will further be noted that in the third embodiment, the end walls are completely separated at the heel and are joined only by the portion 33.

Fig. 7 illustrates another embodiment in which the side walls 40 and 41 of the form are directly interlocked and the tabs shown in the other embodiments are omitted. Formed in the rear end of the wall 41 are spaced slots 42 of the bayonet type while the rear end of the wall 40 carries a button or rivet 43. The rear ends of the walls are overlapped to make heel forming plies and are

secured in the desired position by the engagement of the button or rivet 43 with the selected slot 42.

The shoe form of each of these embodiments is preferably made of celluloid or similar resilient or normally stiff sheet material, and may be made in accordance with the process disclosed in my Patent No. 1,633,075, dated June 21, 1927. In order to facilitate bending the ends of the side walls around the last in order to make the heel, the heel portions and tabs of the side walls are moistened, preferably by dipping in alcohol or acetone and held in the proper position around the last until dried.

It will be understood that when a full form is inserted in a shoe it is necessary that the bottom of the heel be contracted, and in order to facilitate this movement the ends of the side walls terminate at a distance from each other, as shown in the accompanying drawings. The tab 11 of the first embodiment and the tab 24 of the second embodiment do not prevent this deformation of the heel although offering a yielding resistance to the movement. After either form 10 or 20 has been inserted in a shoe the portions 11 or 24 act upon the end of the side wall against which they rest, to cause the lower ends of the end walls to separate, and the form to resume the normal position shown in Figs. 2 and 5. It will be understood that an examination of the shoe into which the form is to be placed will indicate to the operator the relative position of the heel members when in the shoe, and in the first embodiment the tab 12 is inserted into the proper slot 16 in the wall 15 before the form is inserted into the shoe. In the other embodiments, however, this is not necessary and in fact is seldom done. The button 25 of the tab 23 or the button 34 of the tab 33 is placed in the forward slot 27 or 35 and after the form has been inserted into the shoe the button 25 or 34, which is of course accessible from within the form, can be easily raised into the main slot and the side walls separated until they come into close contact with the walls of the shoe. The button 25 or 34 is then depressed into the slot 27 or 35, which corresponds most closely with this position. The button 43 of the embodiment shown in Fig. 7 may similarly be located in a slot 42 after the form has been placed in a shoe.

It will be noted that, in each embodiment, when the heel of the form is set in the proper position in the shoe it will support the side walls of the shoe and oppose any tendency of the shoe walls to collapse, due to external pressure. At the same time, when the form is to be removed, the top of the heel can be readily contracted, the ends of the side walls turning upon the attachment of the intermediate tab as a pivot, and the form raised until partially out of the shoe. The top is

then expanded and the bottom of the heel contracted so that the form is removed without further difficulty. In the embodiment shown in Figs. 4, 5 and 6, however, the button 25 or 35 can be removed from the slot and shifted to the forward slot, thus positively drawing the ends of the side walls together and contracting the heel of the form to permit removing the form more easily from the shoe.

While each of the embodiments herein set forth disclose the provision of one or more tabs which form extensions of the side walls of the form it will be, of course, understood that instead of providing two relatively narrow tabs the side walls may be extended and overlapped as shown for example in either of the patents above mentioned. Thus referring for example to Fig. 7 of the drawing the portion 40 may be the end of one side wall and the portion 41 the end of the other side wall. These ends overlapping are joined by the use of the slots 42 and the button 43. It will be understood therefore that I am not limited to the use of these narrow tabs and that the interlocking features of the various embodiments may be employed in connection with the ends of the side walls without departing from the spirit and scope of the invention as set forth in the following claims.

I claim:

1. In a shoe form comprising side walls, the ends of which walls make the heel of the form, a tab projecting from one of said ends, the other end being provided with at least one slot with which the tab engages, and means to limit the movement of the tab in the slot in one direction.

2. In a shoe form comprising side walls, the ends of which walls make the heel of the form, a tab projecting from one of said ends, the other end being provided with at least one slot with which the tab engages, and means carried by the tab to limit the movement of the tab in the slot in one direction.

3. In a shoe form comprising side walls, the ends of which walls make the heel of the form, a tab projecting from one of said ends, the other end being provided with at least one slot with which the tab engages, and means carried by the tab which by contact with one wall of the slot limits the movement of the tab in the slot in one direction and thereby prevents the collapse of the heel.

4. In a shoe form comprising side walls, the ends of which walls make the heel of the form, a tab projecting from one of said ends, the other end being provided with at least one slot with which the tab engages, and a tongue integral with the tab which by contact with one wall of the slot limits the movement of the tab in the slot in one direction and thereby prevents the collapse of the heel.

5. In a shoe form comprising side walls, the ends of which walls make the heel of the

form, a tab projecting from one of said ends, the other end being provided with at least one slot with which the tab engages, the tip of the tab passing through the slot into the interior of the form, and a tongue integral with the tab which bears against the forward wall of the slot and limits the forward movement of the tab in the slot and thereby prevents the collapse of the heel.

6. In a shoe form comprising side walls, the ends of which walls make the heel of the form, a tab projecting from one of said ends, the other end being provided with at least one slot with which the tab engages, the tip of the tab passing through the slot into the interior of the form, and means carried by the tab, which means bears against the forward wall of the slot and limits the forward movement of the tab in the slot and thereby prevents the collapse of the heel.

7. In a shoe form comprising side walls, the ends of which walls make the heel of the form, a tab projecting from each end over the outer surface of the other end, one of the ends being provided with a slot with which the tab from the other end engages, and means for holding said slot engaging tab against movement in one direction whereby the ends of the side walls may be pivotally moved relative to each other.

8. In a shoe form comprising side walls, the ends of which walls make the heel of the form, a tab projecting from each end over the outer surface of the other end, one tab projecting from the top of the end of one side wall, the other tab projecting from the middle of the end of the other side wall, said first named wall being provided with at least one slot with which the tab from the second named wall engages, and means for holding the slot engaging tab against movement in one direction whereby the ends of the side wall may be pivotally moved relative to each other.

9. In a shoe form comprising side walls, the ends of which walls make the heel of the form, a tab projecting from each end over the outer surface of the other end, one tab projecting from the top of the end of one side wall, the other tab projecting from the middle of the end of the other side wall, the first named wall being provided with at least one slot with which the tab from the second named wall engages, and means carried by the slot engaging tab for limiting the forward movement thereof whereby the ends of the side walls may be pivotally moved relative to each other.

10. In a shoe form comprising side walls, the ends of which walls make the heel of the form, a tab projecting from each end over the outer surface of the other end, one tab projecting from the top of the end of one side wall, the other tab projecting from the middle of the other side walls, the first named

wall being provided with at least one slot with which the tab from the second named wall engages and through which the tip of the tab passes into the interior of the form, and a tongue on the tab which limits the forward movement thereof whereby the ends of the side walls may be pivotally moved relative to each other.

11. In a shoe form comprising side walls, the ends of which walls make the heel of the form, a tab projecting from each end over the outer surface of the other end, one tab projecting from the top of the end of one side wall, the other tab projecting from the middle of the other side walls, the first named wall being provided with at least one slot with which the tab from the second named wall engages and through which the tip of the tab passes into the interior of the form, and a tongue on the tab which by its contact with the forward edge of the slot limits the forward movement thereof whereby the ends of the side walls may be pivotally moved relative to each other.

Signed by me at Auburn, New York this 14th day of February, 1930.

WILLIAM J. DE WITT.
